PUMP STRUCTURE

Herbert E. Kempton, Chicago, Ill., assignor to Tut-
hill Pump Company, Chicago, Ill., a corporation
of Illinois

Application July 10, 1936, Serial No. 89,913

2 Claims. (Cl. 103—40)

The present invention relates generally to pump structures. More particularly the invention relates to that type of pump structure which comprises (1) a housing with an inlet and outlet for liquid; (2) a shaft which is journaled in the housing and is adapted to be driven by an electric motor or like power medium; and (3) a gear pump which is mounted in the housing and is connected to the shaft so that it operates during drive of the latter to draw liquid through the inlet and to discharge the liquid under pressure from the housing via the outlet.

One object of the invention is to provide a pump structure of this type which embodies novel means whereby the gear pump is rendered inoperative or ineffective to pump liquid under pressure from the housing via the outlet until the motor driven shaft reaches a predetermined rotational speed.

Another object of the invention is to provide a pump structure of the last mentioned character in which the means for rendering the gear pump inoperative or ineffective to pump liquid under pressure from the housing via the outlet comprises a by-pass leading from the outlet or discharge side of the gear pump and also comprises a valve which serves to control the flow of liquid under pressure through the by-pass and is controlled automatically and in such manner that it remains open during drive of the shaft below the aforementioned predetermined rotational speed.

A further object of the invention is to provide a pump unit of the type and character under consideration which has particular utility in connection with an oil burner of the nozzle and blower type and is adapted to have the shaft for driving the gear pump connected to the impeller wheel of the burner blower for conjoint drive therewith.

A still further object of the invention is to provide a pump structure which is generally of new and improved construction, embodies a novel arrangement of parts, and is extremely efficient in operation.

Other objects of the invention and the various advantages and characteristics of the present pump structure will be apparent from a consideration of the following detailed description.

The invention consists in the several novel features which are hereinafter set forth and are more particularly defined by claims at the conclusion hereof.

In the drawings which accompany and form a part of this specification or disclosure and in

which like numerals of reference denote corresponding parts throughout the several views:

Figure 1 is a view partly in elevation and partly in section of an oil burner and a pump structure embodying one from of the invention;

Figure 2 is a horizontal section on the line 2—2 of Figure 1;

Figure 3 is a vertical longitudinal section of the pump structure of Figure 1;

Figure 4 is a vertical transverse section on the line 4—4 of Figure 3;

Figure 5 is a vertical transverse section taken on the line 5—5 of Figure 3 and showing the plate which is connected to one end of the pump housing and forms with the latter a chamber for the operating parts of the gear pump;

Figure 6 is a plan view of the plate shown in Figure 5;

Figure 7 is a vertical transverse section taken on the line 7—7 of Figure 3 and showing the construction of the gear pump;

Figure 8 is a horizontal section on the line 8—8 of Figure 7;

Figures 9 and 10 are horizontal sections on the lines 9—9 and 10—10 of Figure 3, respectively.

Figure 11 is a vertical longitudinal sectional view of a pump unit embodying another or second form of the invention;

Figure 12 is a detail sectional view of the automatic pump controlling means of the pump structure of Figure 11; and

Figure 13 is an enlarged vertical transverse section on the line 13—13 of Figure 11.

The pump structure which is shown in Figures 1, 2, 3, 4, 5, 6, 7, 8, 9 and 10 constitutes one embodiment of the invention and is adapted for use in connection with an oil burner B.

It is of the internal gear type and operates, as herein-after described, to draw oil from a tank T and force it under pressure to a nozzle b which forms a part of the burner B. As shown in Figures 1 and 2 the burner B embodies, in addition to the nozzle b, a blower b¹ and an electric motor b² for driving the blower. The blower consists of an impeller wheel b³ and a casing b⁴ around the wheel and operates during drive thereof by the motor to supply air under pressure around the nozzle b. The impeller wheel b³ of the blower is fixed to a horizontally extending shaft b⁵ and embodies an annular series of blades b⁶ on the peripheral portion thereof. The casing b⁴ of the blower surrounds the impeller wheel b³ and embodies a pair of end walls b⁷ and b⁸ and a tubular tangentially extending discharge member b⁹. The end wall b⁸ of the blower casing laps one

end of the impeller wheel b^3 and has a circular inlet opening b^{10} in the central portion thereof. The nozzle b to which oil under pressure is supplied by the pump structure is located in the outer end of the tubular discharge member b^9 . When the impeller wheel b^3 is driven air is drawn into the central portion of the casing through the inlet opening b^{10} in the end wall b^8 and is discharged under pressure through the discharge member b^9 . One end of the shaft b^5 is journaled in a bearing b^{11} in the end wall b^7 of the blower casing and is connected in any suitable manner to the armature shaft of the electric motor b^2 . The other end of the shaft extends through the inlet opening b^{10} in the end wall b^8 of the blower casing and is connected to the pump structure so as to drive the latter. The electric motor b^2 is encased in a housing b^{12} which is fixed to the end wall b^7 of the blower casing b^4 . When current is supplied to the electric motor b^2 , the shaft b^5 is driven and operates both the blower and the pump structure. When the pump structure operates to supply oil under pressure to the nozzle b of the burner the oil is atomized by the nozzle and forms a combustible mixture with the air which is delivered by the blower through the tubular discharge member b^9 . This mixture is adapted to be ignited by way of a pair of electrodes b^{13} in the outer or discharge end of the tubular member b^9 . These electrodes receive current through the medium of a pair of conductors b^{14} and are spaced apart for spark forming purposes, as shown in Figure 2.

The pump structure comprises a pump housing 17, an internal gear pump 18, a strainer 19, and a valve unit 20, and is characterized by the fact that it includes novel and simple means whereby it is controlled so that no oil is supplied to the nozzle b of the burner B unless the shaft b^5 is driven at normal speed by the electric motor b^2 . By incorporating means of this character in the pump structure the burner, during starting thereof, receives no oil until the blower is operating at its normal speed and there is a liberal or proper supply of air around the nozzle b . Furthermore, the flow of oil to the nozzle is automatically cut off or stopped before stoppage of the air supply when the burner is shut off or rendered inoperative by cutting off the flow of current to the electric motor b^2 . The pump housing 17 of the pump structure is in the form of an elongated horizontally extending metal casting and is carried by a frame 21 so that it is coaxially positioned with respect to the electric motor b^2 for driving the impeller wheel of the blower. The frame 21, as shown in Figure 1 of the drawings, is fixed to the end wall b^8 of the blower casing b^4 , and includes a vertically extending wall 22. The latter is spaced from said end wall b^8 by way of top and bottom walls 23 which include openings for permitting the flow of air to the inlet opening b^{10} . The pump housing 17 extends through a hole 24 in the vertically extending wall 22 of the frame 21 and embodies a radially extending flange 25. The latter is formed integrally with the central portion of the pump housing and fits against the outer face of the wall 22. Bolts 26 extend through the flange 25 and the vertically extending wall 22 and serve to hold the pump housing 17 in fixed or connected relation with the frame 21. The inner end of the pump housing is cylindrical and has an enlarged bore 27 which forms a centrifugal valve chamber 28 and extends longitudinally of the pump housing. The other or outer end of the pump housing 17

is provided with a flat end face 29 and has a longitudinally extending bore 30. The latter is smaller in diameter than the bore 27 and communicates with the chamber 28. A cylindrical plug 31 fits in the bore 30, as shown in Figure 3, and has a longitudinally extending eccentrically disposed bearing forming hole 32. The inner end of the plug projects into the centrifugal valve chamber 28 and is in the form of a reduced extension 33. The other or outer end of the plug terminates inwardly of the flat outer end face 29 of the pump housing and forms with the outer end of the bore 30 a cylindrical chamber 34 in which the operating parts of the internal gear pump are disposed. The outer end of the shaft 15 b^5 , that is the end of the shaft which extends through the inlet opening b^{10} in the end wall b^8 of the blower casing projects through the bore 27 in the inner end of the pump casing 17 and extends into and is journaled in the bearing 20 forming hole 32 in the cylindrical plug 31. The inner end of the pump housing 17 is closed by means of a fluid tight sealing device 35. The latter serves as an end closure for the bore-formed centrifugal valve chamber 28 and includes 25 a ring 36 which extends around the shaft b^5 and has an external screw thread in engagement with an internal screw thread in the bore 27. The pump housing 17 of the pump structure embodies in addition to the outward or radially extending 30 flange 25 a transversely extending suction port 37 in one side thereof, and a transversely extending by-pass port 38 in its other side. These two ports are positioned one diametrically opposite the other and are located in the lower portion of the 35 pump housing 17. The suction port is connected to the oil tank T by a pipe 39 and the by-pass port 38 of the pump housing 17 is connected to the tank by a pipe 40. During operation of the pump structure oil is drawn from the tank T 40 through the pipe 39 and into the pump housing 17 via the port 37 and then after being drawn through the strainer 19, as hereinafter described, passes to the suction side of the internal gear pump. From the pressure side of the pump the 45 oil is either by-passed back to the tank T via the by-pass plate 38 and the pipe 40, as hereinafter described, or is delivered to the valve unit 20 and there flows part to the burner nozzle b and the remainder via the pipe 40 to the tank T. 50

The internal gear pump 18 is of standard design or construction and consists of a gear 41, a rotor 42, and a crescent 43. The gear 41 of the pump is disposed in the chamber 34 in the outer end of the pump housing 17 and is keyed or otherwise fixedly secured to the shaft b^5 . Due to the fact that the bearing forming hole 32 is eccentrically disposed in the plug 31 the gear 41 of the pump is eccentrically positioned in the chamber 34. The rotor 42 corresponds in diameter to, and fits within, the chamber 34. It is in the form of an internally toothed ring type gear and surrounds and meshes with the gear 41, as shown in Figure 7. The crescent 43, as shown in Figure 7, is stationary. It is formed as an integral part of the plug 31 and fits it and seals the crescent shaped space between the gear 41 and the rotor 42, that is the space where the teeth of the gear are not in mesh with the teeth of the rotor due to the eccentric position of the gear with respect to the rotor. The chamber 34 in which the gear, rotor and crescent of the internal gear pump are disposed is closed at the outer end thereof by means of a plate 44. This plate fits against the flat end face 29 of the pump 55

housing 17 and is secured in place by means of a series of bolts 45. The latter extend through holes 46 in the plate 44 and project into internally threaded sockets 47 in the outer end portion of the pump housing 17. As shown in Figure 5, the plate 44 embodies in the central portion thereof a pair of oppositely facing kidney-shaped slots 48 and 49. The slot 48 is located adjacent to and communicates with one side of the chamber 34 in the outer end of the pump housing 17 and forms the pump inlet. The slot 49 is located adjacent to, and communicates with, the other side of the chamber 34 and constitutes or forms the pump outlet. The inlet of the pump, that is the kidney-shaped slot 48 communicates with the strainer 19, and the pump outlet communicates with and discharges into the valve unit 20, as hereinafter described. When the shaft b⁵ is rotated by the electric motor b² the gear and rotor, due to the fact that they are in mesh, revolve within the chamber 34 and the pump is thus caused to operate. During operation of the pump a partial vacuum is created in the inlet forming kidney-shaped slot 48 in the plate 44. This is attributable to the fact that as the teeth of the gear 41 come out of mesh with the teeth of the rotor 42 here is a suction action in the inlet side of the pump. In response to this action, oil is sucked or drawn from the tank through the pipe 39 and the strainer 19 and flows into the space between the teeth of the gear and the rotor. When the teeth of the gear 41 mesh with the teeth of the rotor 42 at the outlet side of the pump the aforesaid spaces are filled and the oil is forced under pressure out through the outlet forming kidney-shaped slot 49 in the plate 44 and is delivered to the valve unit 20, as hereinbefore described.

The strainer 19 through which the oil passes in transit from the suction port 37 to the internal gear pump 18 is located beneath the outer end of the pump housing 17 and comprises a cup-shaped casing 50 and a series of screen units 51. The casing 50 is secured in place by means of a bolt 52 which extends upwardly through the bottom of the casing and fits within an internally threaded socket 53 in the bottom portion of the front end of the pump housing 17. A gasket 54 is interposed and clamped between the upper margin or edge of the side wall of the casing and the bottom face of the pump housing and serves to prevent leakage of oil from the casing. The units 51 are arranged in superposed relation in the casing 50 and each consists of an outer frame 55, an inner frame 56, and a screen 57 between the two frames. A plate 58 on the shank part of the bolt 52 and a compression spring 59 between the plate and the bottom of the strainer casing 50 serve to hold the screen units in clamped relation and to urge them upwards against the bottom face of the outer portion of the pump housing 17. The inner frames 56 of the screen units 51 have aligned holes 60 therein through which the shank portion of the bolt 52 extends. They are centrally positioned with respect to the outer frames 55 and have offset portions with aligned apertures 61 therein. These apertures 61 communicate with a duct 62 leading downwards from the suction port 37 in the pump casing and permit oil in response to the suction created by the internal gear pump to flow through an aperture (not shown) in the plate 58 into the strainer casing 50. The screens 57 of the units are arranged to form inlet compartments 64 and outlet compartments 65. The inlet compartments 64 are arranged in alternate relation with respect to

the outlet compartments and receive oil from the container casing by way of duct forming grooves 66 in the outer frames 55 of the units. The oil after passing through the grooves into the inlet compartments 64 flows through the screens 57 into the outlet compartments 65 and then passes into aligned apertures 67 in the outer frames 55 of the units. The apertures 67 communicate with the outlet compartments 65 by way of pairs of grooves 68 in the outer frames of the units and communicate with a vertically extending passage 69 in the bottom portion of the outer end of the pump housing 17. The inlet forming kidney-shaped slot 48 in the plate 44 communicates with the passage 69 by way of a horizontally extending passage 70, an arcuate groove 71, a hole 72 and a groove 73. The horizontally extending passage 70 is formed in the outer end of the pump housing 17 and leads from the upper end of the vertically extending passage 69 to the flat end face 29 of the pump housing where it joins and communicates with the arcuate groove 71. The latter is formed in the flat end face 29 of the pump housing and as shown in Figure 7, underlies the chamber 34 in which the operating parts of the internal gear pump are disposed. The hole 72 is formed in the plate 44 and, as shown in Figure 5, is positioned directly beneath the inlet forming kidney shaped slot 48 and so that it registers or communicates with one end of the arcuate groove 71 in the flat end face 29 of the pump housing. The valve unit 20 is located adjacent to the outer end of the pump housing 17 and comprises a body 74. The latter extends vertically and has a flat face 75 which abuts against the outer face of the plate 44. The body of the valve unit is held in place by means of the bolts 45 which, as shown in Figure 10, extend through holes 76 in a pair of laterally projecting lugs 77 on the valve body and operate to hold the flat face 75 in clamped relation with the outer face of the plate 44. The groove 73 is formed in the central portion of the flat face 75 of the body 74 and includes a pair of arcuate branches 73^a and 73^b. The branch 73^a communicates with the branch 73^b and is positioned so that one end thereof registers with the hole 72 in the plate 44. The branch 73^b of the groove 73 registers with the kidney-shaped slot 48 in the plate 44 and assists the latter in forming the inlet for the internal gear pump 18. When the pump is in operation as the result of drive of the electric motor b² suction is created in the kidney-shaped slot 48 in plate 44, as previously pointed out, and as a result of this suction oil flows from tank T into the inlet or suction side of the pump as follows: pipe 39; suction port 37; duct 62; apertures 61 in the inner frames of the screen units 55 of the strainer 19; aperture 63 in the plate 58; interior of casing 50; grooves 66 in the outer frames of the screen units; inlet compartments 64; outlet compartments 65; grooves 68 and aligned apertures 67 in the outer frames of the screen units; passages 69 and 70; groove 71; hole 72; and branches 73^a and 73^b of groove 73.

The valve unit 20 is connected by a pipe 78 to supply oil under pressure from the internal gear pump 18 to the nozzle b of the oil burner and comprises in addition to the body 74 a plunger type valve 79 and a sleeve type valve seat 80. The body 74 is provided with a vertically extending bore 81 in which the plunger type valve 79 is slidably mounted. The valve seat 80 is located in the lower end of the bore 81 and is carried by a plug 82 at the lower end of the body 74.

14. The shank of the plug, as shown in Figure 3, has a centrally disposed vertically extending hole 83 and is provided with an external screw thread in engagement with an internal screw thread in the lower end of the bore. The upper end of the hole 83 is enlarged and forms a socket 84 for the valve seat 80. The pipe 78 is connected to the lower end of the plug 82 by means of a coupling ring 85 and a vertically extending nipple 86. The upper end of the nipple communicates with the hole 83 and fits within an internally threaded socket 87 in the lower end of the plug. The coupling ring 85 surrounds the inlet end of the pipe 78 and serves to connect the pipe to the lower end of the nipple. The portion of the bore 81 which is disposed directly above the plug and sleeve type valve seat is shaped to form an enlarged pressure chamber 88. This chamber communicates with, and receives oil from, the pressure side of the internal gear pump 18, as hereinafter described. The valve 79 is located above the pressure chamber and is urged downwards into seated relation with the valve seat 80 by means of a compression spring 89. When oil is delivered into the pressure chamber 86 under such pressure that it raises the valve against the force of the spring 89 it flows from the pressure chamber to the nozzle b via the sleeve type valve seat 80, the vertically extending hole 83 in the plug 82, the nipple 86, and the pipe 78. The compression spring 89 is located in the upper end of the bore 81 and abuts against and extends between the valve 79 and an adjusting screw 90. The latter extends through the upper end of the body 74 of the valve unit 20 and is secured or fixed in its various adjusted positions by means of a lock nut 91 which fits against the top face of the body 74 and is housed in a cap 92. By adjusting the position of the screw 90 the compression of the spring 89 may be increased or decreased in order to increase or decrease the amount of pressure necessary to unseat the valve 79. The pressure chamber 88 communicates with and receives oil 45 from the kidney-shaped slot 49 which forms the outlet or pressure side of the internal gear pump 18 by way of a groove 93, a hole 94, a groove 95, a hole 96, and a duct 97. The groove 93 is formed in the flat face 75 of the body 74 of the valve unit. It is positioned directly opposite the groove 73 and comprises a pair of substantially concentric arcuate branches 93^a and 93^b. The branch 93^b registers with the kidney-shaped slot 49 in the plate 44 and assists said slot in forming the outlet or discharge side of the gear pump 18. The branch 93^a communicates with the branch 93^b and registers with the hole 94 which, as shown in Figure 5, is formed in the plate 44. The groove 95 is formed in the flat face 29 at the outer end 60 of the pump housing 17 and is located at one side of the chamber 34 and the arcuate groove 71. One end of the groove 95 registers with the hole 94 and the other end registers with the hole 96. The latter, as shown in Figure 5, is formed in the plate 44 and is disposed between and beneath the hole 94 and the outlet forming slot 49. The duct 97 is inclined and leads from the hole 96 to the pressure chamber. When the gear pump 18 is in operation as the result of drive 65 of the electric motor b² the oil which is discharged under pressure by the pump flows to the pressure chamber 88 in the body of the valve unit 20 as follows: kidney-shaped slot 49 in the plate 44; branch 93^b of the groove 93 in the flat face of 70 the body 74 of the valve unit; branch 93^a of the groove 93; hole 94 in the plate 44; groove 95 in the flat face 29 at the outer end of the pump housing 17; hole 96 in the plate 44; and inclined duct 97 in said body 74. When the pressure in the chamber 88 is sufficient to raise and unseat the plunger type valve 79 oil under pressure flows from the chamber to the nozzle b of the burner, as hereinbefore described. In order to permit of the ready discharge to the by-pass port 38 of the excess oil under pressure delivered by the pump into the pressure chamber 88, a horizontally extending passage 98, a hole 99, and an inclined diagonally extending duct 100 are provided. The passage 98 is formed in the body 74 of the valve unit 20 and, as shown in Figure 3, is located a small distance above the pressure chamber 88. It extends or leads from the bore 81 to the flat face 75 of the body 74 and is closed by the plunger part of the valve 79 when the valve is in its closed position. The hole 99 is formed in the plate 44 between and slightly beneath the holes 72 and 96 and registers with the passage 98. The duct 100 is formed in the outer end of the pump housing 17 and leads from the hole 99 in the plate 44 to the by-pass port 38. When the valve 79 is forced upwardly into its open position as a result of the pressure of the oil in the chamber 88 the passage 98 is uncovered and the oil in the pressure chamber flows part to the burner nozzle b via the pipe 78 and part to the tank T via the passage 98, the hole 99, the duct 100, the by-pass port 38, and the pipe 48. By bypassing back to the tank a portion or part of the oil which is delivered to the pressure chamber 88 in the valve unit 20, constant pressure of the oil is maintained at the nozzle of the burner.

The means for controlling the pump structure so that no oil is supplied to the nozzle b of the burner unless the shaft b⁵ is driven at or in excess of a predetermined speed by the electric motor b² comprises a sleeve valve 101, a plurality of balls 102, and a ball controlled thrust member 103. The valve 101 is disposed in the centrifugal valve chamber 28 in the inner end of the pump housing 17. It is slidably mounted on the shaft b⁵ and serves to control the entry of oil under pressure into the centrifugal valve chamber 28 from an annular groove 104 in the shaft b⁵. Oil under pressure is adapted to flow from the outlet or pressure side of the internal gear pump 18 to the groove 104 by way of a groove 105, a duct 106, and a plurality of holes 107. The groove 105 is formed in the inner face of the plate 44 and communicates with and receives oil from the outlet forming kidney-shaped slot 49 in said plate. The duct 106 is formed in and extends longitudinally through the outer end of the shaft b⁵, that is the end of the shaft which is disposed in the pump housing 17. One end of the duct 106 extends through the extreme outer end face of the shaft and registers with the groove 105 in the plate 44, and the other end of the duct communicates with the groove 104 by way of the holes 107 which are formed in and extend radially with respect to the shaft b⁵. The centrifugal valve chamber 28 communicates with the by-pass port 38 by way of a passage 108. The sleeve valve 101 fits snugly around the shaft b² and is adapted when slid in the direction of the plate 44 and the valve unit 20 to cover the annular groove 104 and when slid in the opposite direction, that is towards the ring 36 of the fluid tight sealing device 35 to expose the groove 104. When the valve 102 is in its open position oil under pressure flows 75

from the outlet or discharge side of the centrifugal gear pump 18 through the groove 105 to the longitudinal duct 106 in the shaft b⁵, and then flows outwardly through the radially extending holes 107 and the annular groove 104 into the chamber 28. From this chamber the oil flows via the duct 108 to the by-pass port 38 and thence through the pipe 40 to the tank. Because of the flow of oil to the by-pass port when the valve 101 is in its open position, there is not sufficient pressure in the pressure chamber 88 of the valve unit 20 to raise the plunger type valve 79 and hence there is no flow of oil from the pump 18 to the nozzle of the burner. When the valve 101 is in its closed position so that it overlies or covers the annular groove 104 the flow of oil from the outlet or discharge side of the pump to the chamber 28 is cut off and all of the oil which is pumped by the pump is delivered to the pressure chamber 88 from whence it flows part to the burner B and part back to the tank T via the passage 98, the hole 99, the duct 100, the by-pass port 38, and the pipe 40, as hereinbefore described. The balls 102 in conjunction with the ball controlled thrust member 103 operate automatically to shift the valve into its closed position when the shaft b⁵ reaches its proper rotational speed, and a compression spring 109 operates to shift the valve into its open position when the speed of the shaft b² is below normal. The balls 102 are mounted in an annular carrier 110 which is fixed to rotate with the shaft b⁵ and embodies radially extending pockets 111 for the balls. As shown in Figure 3, the balls 102 are loosely mounted in the pockets and are adapted during rotation of the shaft and the carrier, and in response to centrifugal force or action, to fly outwards. The pockets 111 extend around the inner end of the valve 101. The thrust member 103 is annular and is formed integrally with the central portion of the sleeve valve 101 and embodies a conical or cam type wall 112. The latter bears against the outer portions of the balls 102, as shown in Figure 3. The ball controlled thrust member and the sleeve valve are suitably held against rotation but are free to slide or move lengthwise of the shaft. During drive of the shaft b⁵ the carrier 110 and the balls 102 rotate. When the speed of the shaft is such that the centrifugal force of the balls 102 is sufficient to overcome the action of the compression spring 109 the balls fly or move outwards and due to the cam action of the wall 112 shift the thrust member towards the outer end of the pump housing 7 and thus shift the sleeve valve into its closed position. When the speed of the shaft b⁵ decreases as the result of stoppage of the electric motor b² or for any other reason, the spring 109 overcomes the centrifugal action of the balls 102 and shifts the thrust member together with the sleeve valve towards the ring 36 of the sealing device 35 into a position wherein the annular groove 104 in the shaft b⁵ is exposed and the internal gear pump, as the result of by-passing of the oil via the chamber 28 and the passage 108 is thus inoperative to pump oil through the nozzle b of the burner. The spring 109 surrounds the shaft b⁵ and fits between a pair of rings 113 and 114. The ring 113 fits around and is slidably mounted on the reduced extension 33 at the inner end of the plug 31 in the bore 30. The ring 114 is mounted on the end of the sleeve valve that is nearer the annular groove 104 in the shaft b⁵ and abuts against the ball controlled thrust member 103.

Pin and slot connections 115 between the two rings serve to hold the rings against relative rotation but permit them to move to and from one another. In order to adjust the compression of the spring 109 a screw 116 is provided. This screw extends through the top wall of the pump housing 7 and abuts against a tapered surface 117 on the ring 113. When the screw is turned so that it moves toward the ring 113, said ring in response to the action of the tapered surface 117 moves axially toward the ring 114 and increases the compression of the spring 109. When the screw is moved in the opposite direction, that is away from the ring 113, the ring is permitted to move away from the ring 114 and this results in a decrease in the compression of the spring 109. When the compression of the spring is increased the force tending to counteract the centrifugal action of the balls 102 is increased with the result that the shaft b⁵ must rotate at a higher speed before the sleeve valve 101 is caused by the balls and the thrust member to move into its closed position wherein it shuts off the by-passing of oil to the by-pass port 38 and causes the internal gear pump 18 to supply oil via the pipe 78 to the nozzle b of the burner. When the compression of the spring 109 is decreased by manipulating the screw so that the ring 113 moves toward the body 74 of the valve unit 20 the spring force tending to counteract the centrifugal action of the balls 102 is lessened or decreased with the result that it is not necessary for the shaft to rotate at such a high speed before the balls and carrier operate to shift the sleeve valve 101 into its closed position. The ring 113 and the screw 116 exemplify a simple instrumentality for setting the speed at which the shaft must rotate before oil is pumped by the internal gear pump 18 to the nozzle b of the burner.

The operation of the pump structure of Figures 1 to 10 inclusive is as follows: When the shaft b⁵ is stationary and the burner B is hence inoperative the plunger type valve 79 of the pump unit 20 is closed and the sleeve valve 101 on the shaft b⁵ due to the action of the compression spring 109 is in its open position. When the burner is started by closing the switch for the electric motor b² the shaft b⁵ at first rotates slowly and then picks up in speed until the armature of the motor reaches its normal speed. As soon as the shaft b⁵ starts to rotate the impeller wheel b³ of the blower b¹ operates to draw air through the inlet opening b¹⁰ into the blower casing b⁴ and to force the air under pressure through the tubular discharge member b⁹ and thence around the burner nozzle b. In addition the internal gear pump 18 starts to draw oil from the tank T through the pipe 39, the suction port 37, the strainer 19, and the passageway consisting of passages 69 and 70, groove 71, hole 72, grooves 73 and slot 48, and to force the oil under pressure into the outlet forming kidney-shaped slot 49 in the plate 44. From this slot oil under pressure flows through the groove 105, the duct 106, the cross-holes 107 and the groove 104, into the centrifugal valve chamber 28 and thence via the passage 108 to the by-pass port 38 from whence it flows through the pipe 40 back to the tank T. During the initial or slow speed drive of the shaft b⁵ and while the sleeve valve 101 is in its open position, the plunger type valve 79 of the valve unit 20 remains closed and no oil flows from the pressure chamber 88 to the nozzle b of the burner. As soon as the shaft b⁵ reaches the normal operating speed the sleeve valve 101 is shifted into its closed position and the plunger type valve 79 is shifted into its open position so that oil flows from the pressure chamber 88 to the nozzle b of the burner. The burner is thus supplied with oil and the burner B is operative.

reaches such a speed that the centrifugal action of the balls 102 is sufficient to overcome the action of the compression spring 109 the balls move outwards and in response to the cam action of the tapered wall 112 shift the thrust member 103 towards the valve unit 20 and thus bring the sleeve valve 101 into its closed position. As soon as the valve 101 is shifted into such position bypassing of the pumped oil through the chamber 10 28 and thence to the by-pass port 38 via the passage 108 ceases and the oil under pressure flows from the outlet side of the pump to the pressure chamber 88 via the passageway consisting of slot 49, groove 93, hole 94, groove 95, hole 96, and duct 97. As soon as the pressure in the chamber 88 is sufficient to collapse the compression spring 89 of the valve unit 20, the plunger type valve 79 moves upwards in the bore 81 and oil under pressure flows from the chamber 20 88 through sleeve type valve seat 80, hole 83, nipple 86, and pipe 78 to the nozzle b of the burner. Due to the automatic action of the valve 101 the gear pump 18 does not operate to supply oil to the nozzle b of the burner until the shaft 25 b⁵ reaches a comparatively high speed and the blower operates to supply a liberal amount of air around the nozzle. By having a liberal supply of air around the burner nozzle b prior to delivery of the oil by the gear pump to the nozzle b it is impossible especially during starting of the burner to have an over-rich explosive type of mixture emanating from the tubular discharge member b⁹ of the blower casing of the burner. When the burner is shut down by closing the 30 switch for the motor b², the shaft b⁵ comes gradually to rest as a result of the fly-wheel action of the impeller wheel and the armature of the motor. As soon as the speed of the shaft b⁵ drops to such an extent that the compression 35 spring 109 is sufficient to overcome the centrifugal action of the balls 102 the spring shifts the thrust member 103 in the direction of the inner end of the pump casing 17 with the result that the balls 102 are caused to move inwards and the sleeve valve 101 is caused to move into its open position. Upon opening of the valve 101 communication is established between the annular groove 104 in the shaft b⁵ and the bore formed 40 centrifugal valve chamber 28 in the inner end of the pump housing 17 and as a result the oil which is pumped by the pump is by-passed back to the tank T, as hereinbefore described, and does not flow through the pipe 78 to the burner nozzle. By automatically stopping the flow of oil 45 immediately upon stoppage of the flow of current to the electric motor b² and while the impeller wheel b³ of the blower is still revolving or in operation there can be no free oil or unburnt oil vapor at the discharge end of the burner. By 50 adjusting the screw 116 the pump structure may be set so that the gear pump is operative to supply oil under pressure from the valve unit 20 when the shaft b⁵ reaches any desired rotational speed.

60 In order to vent the space above the plunger type valve 79 of the valve unit 20 and thus permits said valve 79 readily to move upwards when the sleeve valve 101 is closed and pressure develops in the enlarged pressure chamber 88, a passageway 118 between the centrifugal valve chamber 28 and the upper end of the bore 81 is provided. This passageway consists of a longitudinally extending duct 119 in the upper portion 65 of the outer end of the pump housing 11, a hole 70 120 in the plate 44 and an inclined duct 121 in

the upper end of the body 14 of the valve unit.

The pump structure which is shown in Figures 11, 12 and 13 constitutes another form or embodiment of the invention. It is adapted to be used in connection with an oil burner in the same manner as the pump structure of Figures 1 to 10 inclusive, and comprises a pump housing 17^a, an internal gear pump 18^a, a strainer 19^a, and a valve unit 20^a. The pump housing 17^a is exactly the same in design and construction as the housing 17 of the pump structures of Figures 1 to 10 inclusive and embodies a centrifugal valve chamber 28^a in the inner end thereof and a plug 31^a in its outer end. The plug 31^a has a chamber 34^a for the various operating parts of the internal gear pump 18^a, and also has a longitudinally extending bearing forming hole 32^a in which is journaled the outer end of the impeller driving motor driven shaft of the burner with which the pumping unit is associated. As shown in Figure 20 11, the end of the shaft which is journaled in the hole 32^a has an annular groove 104^a, a longitudinal duct 106^a between the groove and the pump 18^a, and a plurality of radially extending holes 107^a between the inner end of the duct 106^a and the groove 104^a. The housing 17^a of the pump structure embodies a suction port (not shown) in one side thereof and a by-pass port 38^a at the other side thereof and has a passage 108^a between the centrifugal valve chamber 28^a and the by-pass 30 port 38^a. The duct 106^a, the cross-holes 107^a, the annular groove 104^a, the centrifugal valve chamber 28^a, and the passage 108^a constitute a by-pass connection between the outlet or discharge side of the centrifugal pump 18^a and the by-pass port 38^a. The internal gear pump 18^a, the strainer 19^a, and the valve unit 20^a, are respectively the same in design and construction as, and operate similarly to, the gear pump, strainer and valve unit of the pump structure of Figures 1 to 10 inclusive. A plate 44^a corresponding in design to the plate 44 of the previously described pump structure fits between the outer end face of the pump housing 17^a and the body of the pump unit 20^a. Said pump unit 20^a includes a 45 plunger type valve 79^a, and a sleeve type valve seat 80^a, and has a pressure chamber 88^a, which is connected to the discharge side of the gear pump.

The pump structure of Figures 11, 12 and 13 50 is exactly the same as that of Figures 1 to 10 inclusive, with the exception that it embodies different means for controlling the by-passing of oil under pressure from the outlet or discharge side of the internal gear pump to the by-pass port of the pump housing. The control means of the pump structure of Figures 11, 12 and 13 comprises a disk-like valve housing 122, and a pair of valve plungers 123. The housing 122 is disposed in the centrifugal valve chamber 28^a in the 55 pump housing 17^a and extends around and is fixed to rotate with the motor driven shaft. As shown in Figure 11, the housing surrounds the annular groove 104^a in the shaft and includes a pair of diametrically opposite radially extending 60 cylinders 124. The valve plungers 123 fit slidably in these cylinders and are adapted during drive of the shaft and in response to centrifugal force to move outwards in the cylinders. The outer ends of the cylinders open into the centrifugal valve chamber 28^a, and have compression 65 springs 125 for urging the valve plungers 123 inwardly towards the shaft. A spring ring 126 fits in an annular groove 127 in the outer periphery of the housing 122 and forms abutments for the 70 75

outer ends of the springs 125. The housing 122, as shown in Figure 11, embodies at one side of the cylinders 124 a pair of diametrically opposite radially extending ducts 128. These ducts extend alongside of the cylinders 124 and communicate at their inner ends with the annular groove 104 in the motor driven shaft. The outer ends of the ducts 128 extend at right angles and lead to, and communicate with, the outer ends of the cylinders for the valve pistons 123. When the motor driven shaft is at rest and the valve pistons are in engagement with the shaft, as shown in Figure 11, the outer ends of the ducts are uncovered or exposed and there is communication between the annular groove 104^a in the shaft and the centrifugal valve chamber 28^a. When the shaft is rotated at such a speed that the valve plungers 123 move outwards against the force of the springs 125, the outer ends of the ducts 128 are covered or closed, as shown in Figure 12, and by-passing of the oil from the internal gear pump 18^a through the valve chamber 28^a to the by-pass port 38^a is terminated.

The operation of the pump structure of Figures 11, 12 and 13 is as follows: When the motor driven shaft starts to rotate, the oil which is pumped by the gear pump 18^a instead of forcing open the plunger type valve 79^a in the valve unit 20^a and flowing out of the body of the valve unit via the sleeve type valve seat 80^a flows through the duct 106^a, the holes 107^a, the annular groove 104^a, and the ducts 128 into the centrifugal valve chamber 28^a. From this chamber the oil flows via the passage 108^a to the by-pass port 38^a in the pump housing 17^a. As long as the shaft is driven at low speed and the valve plungers 123 are held against the shaft by the springs 125 the pump pumps no oil from the valve unit 20^a. When the speed of the motor driven shaft increases to such an extent that the centrifugal force or action of the valve plungers 123 is sufficient to collapse the springs 125 the plungers move outwards and close the outer ends of the ducts 128. As soon as these ducts are closed by-passing of the oil through the centrifugal pump chamber 28^a to the by-pass port 38^a ceases and the oil flows from the pump into the pressure chamber 88^a and then after opening the plunger type valve 79^a flows out of the body of the valve unit 20^a via the sleeve type valve seat 80^a. As long as the motor driven shaft rotates at such a speed that the valve plungers 123 are in closed relation with respect to the outer ends of the ducts 128, the internal gear pump 18^a operates to pump oil from the valve unit 20^a. As soon as the rotational speed of the shaft drops to such an extent that the springs overcome the centrifugal action of the valve plungers and force the valve plungers inwards against the shaft, the pump, due to the by-passing action of the oil, is rendered inoperative. By substituting springs with greater or less compression for the springs 125 the pump structure may be set so that pumping of oil from the valve unit 20^a is obtained at either higher or lower speeds of the shaft.

The herein described pump structures are comparatively simple as far as construction and design are concerned and may be manufactured at a low and reasonable cost. They are extremely efficient in operation due to the automatic control means.

Whereas the aforementioned pump structures have been described in connection with oil burners and the pumping of oil, it is to be understood that they may be used for other purposes and 75 in connection with the pumping of other liquids.

It is also to be understood that the invention is not to be restricted to the details set forth, since these may be modified within the scope of the appended claims, without departing from the spirit and scope of the invention.

Having thus described the invention what I claim as new and desire to secure by Letters Patent is:

1. A pump structure of the character described comprising in combination an elongated housing embodying a pump chamber in one end thereof with a suction and a pressure side and a second chamber in its other end and having a fluid inlet and an outlet leading respectively to the suction and pressure sides of said pump chamber, a drive shaft journaled in the housing so that it extends through the two chambers and having a by-pass forming longitudinal duct therein with one end thereof connected to the pressure side of the pump chamber and its other end communicating with said second chamber, rotary pump means in the pump chamber connected for drive by the shaft and operative during drive to draw fluid through the inlet and deliver it under pressure to the outlet and said by-pass forming duct, a valve in said second chamber for controlling said duct, means mounted in said second chamber on the shaft and controlled by the rotative speed of the shaft for automatically closing the aforesaid valve when the shaft reaches a predetermined speed and automatically opening said valve when the shaft drops below a certain speed, and a pressure opening valve disposed in, and operative to control the outflow of fluid through, the outlet and adapted when the duct controlling valve is closed during pump operation and the pressure of the pumped fluid against it is thus increased to open and permit the pumped fluid to flow through the outlet and when said duct controlling valve is opened and the pressure of the fluid against it is thus decreased to close the outlet against outflow of the pumped fluid therethrough.

2. A pump structure of the character described comprising in combination an elongated housing embodying a pump chamber in one end thereof with a suction and a pressure side and a second chamber in its other end and having a fluid inlet and an outlet leading respectively to the suction and pressure sides of said pump chamber, a drive shaft journaled in the housing so that it extends through the two chambers and having a by-pass forming longitudinal duct therein having one end thereof communicating at all times with the pressure side of the pump chamber and provided at its other end with a cross-hole leading to said second chamber, rotary pump means in the pump chamber connected for drive by the shaft and operative during drive to draw fluid through the inlet and deliver it under pressure to the outlet and said by-pass forming duct, a sleeve valve in said second chamber mounted slidably on the cross-shaft and adapted when slid in one direction to lap the cross-hole and close the by-pass and when slid in the other direction to expose the cross-hole and open the by-pass, centrifugal governor means mounted in said second chamber on the shaft and controlled by the rotative speed of the latter so that it operates automatically to shift the sleeve valve in said one direction for by-pass closing purposes when the shaft reaches a predetermined speed and to shift the sleeve valve in the opposite direction for by-pass opening purposes when the shaft drops below a certain speed, and a spring closed pressure opening valve dis-

posed in, and operative to control the outflow of fluid through, the outlet and adapted when the by-pass is closed during pump operation and the pressures of the pumped fluid against it is thus increased to open against the force of its spring and permit the pumped fluid to flow through the

outlet and when said by-pass is opened and the pressure of the fluid against it is thus decreased to close in response to action of said spring and prevent outflow of the pumped fluid through the outlet.

HERBERT E. KEMPTON.
